M. C. LONGACRE, OF CLEVELAND, OHIO.

Letters Patent No. 83,291, dated October 20, 1868

IMPROVED STEP-LADDER.

The Schedule referred to in these Letters Patent and making part of the same.

To all whom it may concern:

Be it known that I, M. C. LONGACRE, of Cleveland, county of Cuyahoga, in the State of Ohio, have invented a new and improved Step-Ladder; and I do hereby declare that the following is a full and exact description thereof, reference being had to the accompanying drawings, and to the letters of reference marked thereon.

Figure 1 is a side view.

Figure 2 is a front view.

Figure 3 is a horizontal section in the direction of the line x x , fig. 1.

The nature of this improvement relates to the construction of a step-ladder that shall be perfectly stiff in all its parts, and also having a brace from the front of the ladder to the support, which secures them firmly together, thus enabling the structure to stand firm, and it may be moved about roughly without endangering the joints, and which will not spring or shake, and is portable.

To enable others to fully understand this improvement, and by what means the above advantages are accomplished, I will describe its construction.

This ladder is similar to those now in use, consisting of the two uprights A, between which the steps B are secured, and held in place by any suitable means, the legs C, that support the ladder, being hinged to the front of said ladder, as in the ordinary manner.

The uprights A and legs C are provided each with a rib, a a' . These ribs, as shown, are put on the strips A in a curve, the ribs being made thicker near the centre than at either end, as shown in fig. 2. The object of these ribs is to prevent springing and shaking of said strips; also to aid in strengthening. The steps B are provided with a similar rib, a'' , secured by screws, or otherwise, underneath and near the front of said

steps, and are designed to strengthen them, and prevent springing when trod upon, or bearing the weight of a person.

D is a brace, hinged to the support C, a top view being shown in fig. 3. This brace is provided, at the opposite end, with a metallic plate, b, in which is cut a slot, c. This brace, being provided with a slot, is secured, by means of the button d, to the step of the ladder, as shown, thus firmly securing and preventing the support C from being pushed or slipped out of place, also holding it so firmly that the ladder can be moved round and handled roughly, without injury or damage to said ladder.

When the ladder is not in use, the brace can be folded against the support, and secured by the button e, the brace or support C closing against the steps in the ordinary way, being held by the hook and eye f.

I I are braces for strengthening and sustaining the joints of the ladder.

The ladder possesses, by this method of construction, greater strength, stiffness, and durability, and is but a trifle heavier, than the skeleton ladder in use. It is, therefore, much safer, because not liable to be thrown down. The shaking or trembling is entirely overcome, which so much endangers the person using the light and weak skeleton ladder.

What I claim as my improvement, and desire to secure by Letters Patent, is—

The slotted metallic plate b c, in combination with the hinged brace D, and buttons d e, when used in connection with a step-ladder, substantially as and for the purpose described.

M. C. LONGACRE.
